UNITED STATES PATENT OFFICE.

FRANK J. GOLDSOLL, OF NEW YORK, N. Y., ASSIGNOR TO M. TECLA & COMPANY, A CORPORATION OF NEW YORK.

DESIGN FOR A DISPLAY-BOARD.

45,417.

Specification for Design.

Patented Mar. 17, 1914.

Application filed March 14, 1912. Serial No. 683,864. Term of patent 14 years.

To all whom it may concern:

Be it known that I, FRANK J. GOLDSOLL, a citizen of the United States, and a resident of New York city, in the county of New York and State of New York, have invented a new, original, and ornamental Design for a Display-Board, of which the following is a specification, reference being had to the accompanying drawings, forming part thereof.

Figure 1 is a front elevational view of a display board showing my new design. Fig. 2 is a plan view thereof.

A panel A, having a plane display surface, has mounted thereon a bracket candelabra A' and is surrounded by a suitably carved frame. At the top of the panel A, a panel C is provided having a frame B. The name of the proprietor may be displayed on this panel C. A carved portion E is formed on each side of the frame B.

Extending from each side of the frame of panel A is a framed panel F arranged at an angle to the panel A as shown in Fig. 2. Projecting from the outer edges of said panels F are panels G arranged in alinement with each other. Candelabra, of substantially the same design as shown in panel A, are mounted on panels G.

The design is particularly adapted for window dressing displays and the like.

I claim—

The ornamental design for a display board having the panels and candelabra substantially as shown and described.

F. J. GOLDSOLL.
